[57] CLAIM

The ornamental design for a rope chain, as shown and described.

DESCRIPTION

FIG. 1 is a front elevational view of a rope chain showing my new design, the rear and side elevational views being identical;

FIG. 2 is an end elevational view, the opposite side being identical;

FIG. 3 is an enlarged cross sectional view taken along the lines 3—3 of FIG. 1;

FIG. 4 is a front elevational view of a rope chain showing a second embodiment of my new design, the rear and side elevational views being identical;

FIG. 5 is an enlarged cross sectional view taken along the lines 5—5 of FIG. 4;

FIG. 6 is a front elevational view of a jewelry chain showing a third embodiment of my new design; and,

FIG. 7 is an enlarged cross sectional view taken along the lines 7—7 of FIG. 6.
